HUMIDOSTAT

Even J. Rohne, Minneapolis, Minn., assignor to
George G. Struthers, Minneapolis, Minn.

Application July 12, 1934, Serial No. 734,830

21 Claims. (Cl. 200—52)

This invention relates to a humidostat or an instrument for responding to differences in humidity in a living or other room. It is now considered quite important and is quite common to regulate the humidity in rooms in which people are located, by supplying moisture thereto when the humidity is low. Such moisture supplying devices must be regulated and it is necessary to have a humidostat for regulating the same which is quite delicate and will respond to small differences in the humidity, and which will have a positive movement so that it can regulate the humidifier. Such regulation is usually accomplished by having the humidostat make and break an electric circuit. It is also desirable that a humidostat have means for indicating the relative humidity so that the humidity in the room can be known by observing such means.

It is an object of this invention, therefore, to provide a simple, delicate, accurate and positively acting humidostat which will respond to small differences in the degree of humidity.

It is a further object of the invention to provide a novel method of constructing such a humidostat.

It is still another object of the invention to provide a simple and efficient humidostat comprising an elongated member made of hard wood, having the fiber of the wood running transversely thereof, one side of said member being sealed against contact with the air by a flexible and extensible means, and one end of said member being rigidly held so that said member will flex with changes in humidity.

It is still another object of the invention to provide a humidostat comprising an elongated piece of hard wood, especially treated to fix the fiber, one side of said member being sealed by having secured thereto a flexible and extensible means impervious to moisture, said member being fixed at one end and free at its other end, preferably having a metallic rod extending lengthwise thereof, said member carrying means at its upper end to engage contacts at either side thereof, whereby when said member is flexed it will engage and disengage said contact, said contacts being arranged to operate an electrical circuit.

It is a further object of the invention to provide a humidostat having a casing, an elongated member adapted to flex with variations in the humidity secured adjacent one end in said casing, a second member secured to said member at its free end and extending alongside of the same

in spaced relation thereto and reversely disposed as to its flexing characteristics, said last mentioned member carrying an electrical contact adapted to engage and disengage an electrical contact carried by said first mentioned member. 5

It is also an object to provide such a device as set forth in the preceding paragraph, said casing having an indicating means thereon actuated by the flexing of said first mentioned member, means also being preferably provided to adjust the position of said first mentioned member. 10

It is a further object of the invention to provide such a structure as set forth in the two preceding paragraphs, said second mentioned contact being adjustable from without said casing and said last mentioned means being accessible for manipulation from without said casing. 15

These and other objects and advantages of the invention will be fully set forth in the following description made in connection with the accompanying drawings, in which like reference characters refer to similar parts throughout the several views, and in which:—

Fig. 1 is a perspective view of the device; 20

Fig. 2 is a top plan view;

Fig. 3 is a view similar to Fig. 1 and partly in vertical section showing a modified form of the invention.

Fig. 4 is a horizontal section taken on line 4—4 of Fig. 3; 25

Fig. 5 is a view in front elevation of a modified form of the device including a casing;

Fig. 6 is a view of the device in rear elevation with the rear cover of the casing removed;

Fig. 7 is a vertical section taken substantially on line 7—7 of Fig. 6 as indicated by the arrows; 30 and

Fig. 8 is a horizontal section taken on line 8—8 of Fig. 6 as indicated by the arrows.

Referring to the drawings, a device is shown 40 comprising a base member 10. While this base member may be variously made of different kinds of material, in the embodiment of the invention illustrated it is shown as formed of a rectangular piece of metal. Angle brackets 11 45 are secured to the base member 10 adjacent one end thereof, and an elongated flexible member 12 is rigidly secured between the upstanding ends of brackets 11 by some suitable means such as a headed and nutted bolt 13. The member 12 comprises a bar 12a and a layer of material 12b at one side thereof. While the member 12a may be made of various shapes, in the embodiment of the invention illustrated it is shown as trapezoidal in horizontal cross section, with 50 55

the parallel sides of the trapezoid as the sides of the bar, and the converging sides as the front and rear. The bar 12a is preferably made of some wood, preferably hardwood, such as maple 5 and the same is preferably cut across the fiber or grain of the wood so that said grain extends transversely of the bar. Said bar is shown as being of somewhat greater rectangular cross sectional area at its bottom where it is secured 10 between brackets 11, than at the portion above said brackets. In making the instrument the bar 12a is first shaped and then the wood is thoroughly dried. After the wood has been perfectly dried it is treated with some suitable 15 chemical to fix the fiber of the wood or insure that the fiber will retain its natural structure. While various chemicals may be used, in practice it has been found suitable to treat the wood with a solution of permanganate of potash.

20 After the wood has been saturated with this solution it is again dried thoroughly, preferably with the application of heat. After the bar is thus dried, the material 12b is placed thereon. While various materials which are quite flexible 25 and somewhat stretchable or extensible could be used, in practice it has been found suitable to use three or four layers of coarse linen glued onto the side of the member 12a and secured thereto by the application of heat and pressure.

30 Waterproof glue is used in the application of the layer 12b. Before the material 12b is applied, a groove 12c is formed in the wide side of the bar 12 and a metallic rod 14 is placed in this groove, which rod may also be glued in 35 place. The rod 14 extends from the top to the bottom of bar 12a. When the layer of material 12b has been applied to the bar and the same has dried thoroughly, the bar can be secured in the brackets 11. A member 15 of material forming 40 a conductor for electricity, such as metal, is secured to the upper end of bar 12 and in the embodiment of the invention illustrated said member is shown as a three-sided rectangular cap extending over the top and along the sides 45 of said bar. A standard 16 extends upward from base 10 close to the bar 12 and binding posts 17 and 18 are secured in said standard, the same having the outwardly extending adjustable pins 17a and 18a split at their outer 50 ends. Comparatively small screws 17b and 18b extend transversely through the pins 17a and 18a respectively, the same having slotted heads and having pointed ends disposed closely adjacent the cap 15. A conductor 19 forming one 55 side of one electric circuit is connected to the binding post 17 and another binding post 20 may be provided in some convenient location. In the embodiment of the invention illustrated, the binding post 20 is shown as carried in the 60 lower portion of the post 12a. The binding post 20 will be connected by a slack conductor 21 to the cap 15 and a conductor 22 leading from binding post 20 will constitute the other side of said electric circuit. A second electric circuit is 65 provided, and conductor 29 forms a part thereof and is connected to binding post 18. The conductor 30 also connected to binding post 20 forms the other side of this second circuit.

In operation the device will be disposed in a 70 room where it is desired to regulate the humidity. The electric circuits comprising conductors 19, 22 and 29, 30 will include relays or solenoids which will be arranged to control the humidifier. The screws 17b and 18b will be adjusted so that at the desired degree of humidity

in the room cap 15 will be out of contact with said screws. Should the humidity decrease, moisture evaporates from the bar 12a and the same bends toward the right as shown in Fig. 1, thus bringing cap 15 into engagement with the screw 17b. This closes the electrical circuit comprising conductors 19 and 22 and more moisture or vapor will be discharged into the atmosphere of the room. When bar 12 thus moves to the right, the material 12b is flexed and since it is secured to the bar along its length, it must stretch or increase in length longitudinally slightly. The material used for the layer 12b is of such a nature that this is readily permitted. As soon as the humidity reaches the desired degree, bar 12a will absorb moisture and the same will move toward the vertical, thus disengaging cap 15 from screw 17b. Should the humidity increase beyond the desired point the bar 12 will move to the left as shown in Fig. 1 and cap 15 will be brought into engagement with the screw 18b. This will close the electrical circuit comprising conductors 29 and 30 and the control mechanism will act to stop the discharge of moisture into the room. The metallic rod 14 adds strength and firmness to the bar 12 and acts to stabilize the device. This bar renders it possible to locate the position of bar 12 between the screws 17b and 18b so that it will flex in either direction with changes in humidity. The bar also acts to insure that positive make or break engagement will be made with one of the screws 17b and 18b. The rod tends to resist the flexing of the bar 12 and appears to permit the flexing in small jerks or increments. This causes a good contact when screws 17b and 18b are engaged and makes a positive break when the bar flexes away from said screws. The treating of bar 12a with the chemical solution and the thorough drying of the bar which is done with a high degree of heat, renders the cells of the wood quite dead and free from any natural moisture. After such treatment the wood is not greatly affected by changes in temperature and bar 12 will not flex with changes in temperature. The bar, however, is quite sensitive to changes in humidity.

In Fig. 3 a modified form of the invention is shown. Instead of having the cap 15 on top of the bar 12, a pin 24 extends through the top of the bar and is in engagement with rod 14. Small plates 25 are disposed at the ends of pin 24 and these will engage the screws 17b and 18b. A binding post or screw 26 is secured adjacent the bottom of bar 12, which screw or post is in engagement with rod 14. The conductor 27 can be secured between nuts 28 on binding post 26. It will be seen that the current from the screws 17b and 18b will be conducted through rod 14 to the binding post 26 and the conductor 21 shown in Fig. 1 is thus unnecessary. Otherwise, the operation of the form shown in Fig. 3 is the same as that already described.

The wood used can, of course, be varied, a hard wood preferably, though not necessarily, being used. The wood may be treated chemically by either immersing the same for a period of time in the solution at ordinary temperature, or the solution may be heated. The treatment with the chemical solution has the effect of drying the wood and after the wood has been dried by heat after being treated, moisture readily evaporates from or leaves the wood when the humidity decreases. It will also be understood that other methods of sealing one side of the

wood member may be used. The purpose of the invention is to seal one side against moisture and arrest any action of the moisture on the cells on this side, at the same time permitting flexing of the wood member due to the moisture changes.

Referring to Figs. 5 to 8, a device is shown comprising a casing 35 having an upper portion of octagonal shape and a lower substantially rectangular portion extending therefrom. Said octagonal portion of the casing has a front surface about which extends a circular raised rib 35a and said lower portion has a flat front surface disposed at a lower level than the front of said upper or octagonal portion. A side wall or flange 35b extends rearwardly from the front of the casing, the same flaring outwardly toward its free edge. Said side wall is provided with a plurality of slots or openings 35c providing free ventilation of air through said casing and said casing is preferably closed at its rear by a thin plate 36 secured to the flange 35b by a plurality of screws 37. Casing 35 has a lug 35d upstanding from its front wall in which is secured a screw 38 forming a post. An elongated member or strip 39 having the general structure of the member 12 already described has metal plates 40 secured thereto at its top and bottom and the screw 38 extends through said member and plates. Member 39 is thus fixed to the post 38 so as to be prevented from transverse bodily movement but can be moved about said post as a pivot. A small metallic rod 41 extends through strip 39 adjacent one side thereof. Said side is also covered with a strip of fabric 39a which will be made of leather or the coarse linen already described as comprising member 12b. Member 39 has a metal plate 42 secured to said side adjacent its lower end, said plate depending below said member. A screw 43 has one end threaded into the depending portion of plate 42 and is journaled in a lug 35e upstanding from the front of casing 35. Screw 43 has a slotted head at the outer side of lug 35e and has a collar 44 secured thereto engaging the inner side of said lug so that endwise movement of said screw is prevented. Collar 44 can be secured in any suitable manner as by the pin 45 as shown. The head of screw 43 is in alignment with a hole 35g formed in one side of casing 35. Member or bar 39 is shown as tapered toward its upper end and another member 46 is provided made of the same material as member 39 or some material which will flex with the variations in humidity. Member 46 is secured to the upper end of member 39, a spacing block 47 being disposed between said members, the upper ends of said members being disposed in the same plane. Member 46 also has a strip of fabric 46a along its side remote from member 39, similar to fabric strip 39a. Member 46 is tapered toward its lower end and as shown in Fig. 6 the same extends downwardly alongside of and spaced from member 39. It will also be noted that it is reversely disposed to member 39 as to its flexing characteristics, the strip 46a being at the side opposite member 39. A headed screw 48 extends through the upper ends of members 39 and 46 having a nut 49 thereon. An electrical conductor or wire 50 extends from one end of screw 48, being secured beneath nut 49, to a screw 51 threaded into the lower portion of member 46 and securing thereto a metallic strip 52. Strip 52 is bent as shown in Fig. 6 and its lower end acts as an electrical contact adapted to engage and dis-

engage the end of a screw 53 forming a cooperating contact, said latter screw extending through member 39 and through an opening 35f in casing 35 and being provided with an operating handle or wheel 53a at its outer end. A small plate 54 is secured to the side of member 39 by a suitable screw 55 and screw 53 is threaded in plate 54. It is obvious that screw 53 can be adjusted by turning wheel 53a and this adjustment can be made from without the casing 35. Another screw 56 is threaded into the member 39 and an electrical conductor or wire 57 extends from the screw 48 to screw 56. Another electrical conductor 58, shown as a covered wire, extends from screw 56 to an electrical socket 59 which is secured in the lower central portion of casing 35. Another electrical conductor 60, shown as a covered wire, is secured to screw 55 and also extends to socket 59. Conductors 58 and 60 are connected respectively to the electrodes of socket 59 which is adapted to receive a suitable plug having a cord to connect socket 59 with a suitable circuit.

The member 46 has secured to its upper end and projecting forwardly therefrom a pin 61. This pin extends into a slot 62a formed in the upper end of a gear segment 62 oscillatable on a pin 63 having reduced portions seated in plates 64 and 65, which plates are spaced by a plurality of bushings 66 secured to plate 65, into which are threaded screws 67. Plates 64 and 65 are thus secured together in rigid spaced parallel relation. The plate 65 is vertically movable in guide plates 68 having offset portions extending over the edges thereof and secured by rivets 69 to a plate 70. Plate 65 has a rearwardly extending lug 65a at its upper end into which is threaded the lower end of a screw 71 having a head engaging the upper outside surface of casing 35 and having pinned thereto a collar 72 engaging the inner surface of casing 35. Plate 70 is secured to the casing 35 by a plurality of screws 73. The casing 35 has a circular opening therein somewhat smaller in diameter than the rib 35a and a dial plate 74 is secured between plate 70 and the casing by screws 73, which dial plate is visible through said opening. The gear segment 62 meshes with a pinion 75 having a shaft portion disposed between plates 64 and 65 and having reduced portions forming trunnions 50 journaled in said plates. The forward one of said trunnions extends through a central opening in plate 70 and dial 74 and has disposed on an angular portion thereof a hand 76, a pair of washers 77 being disposed respectively at each side of said hand and the outer one being held in place by a pin 77a extending through said trunnion. A glass plate or crystal 78 is seated on the front of casing 35 within the rib 35a and a ring 79 of trough-shape in cross section fits over the rib 35a and has its inner edge engaging the plate 78. Ring 79 is held in place by a pair of screws 80 threaded into the rib 35a. The dial plate 74 will have certain indicia thereon indicating the degree of humidity as shown in Fig. 5.

In operation, casing 35 will be disposed in the room to be humidified and preferably secured to the wall. The member 39 will be set relatively to the gear segment 62 so that the hand 76 will register with the correct indicia on the dial plate 74. The plates 64 and 65 can be raised by screw 71 and this varies the position of pin 61 in slot 62a. If pin 61 is at the top of said slot segment 62 will be moved farther by a certain flexing 75

movement of strip 39 than if said pin is near the bottom of said slot. An accurate adjustment of the movement of hand 76 relative to the dial can thus be secured. Strip 39 and hand 76 can also be set at a desired point by turning screw 43. It will be seen that screw 43 is accessible from the outer side of the casing by inserting a screwdriver through the hole 35g. The socket 59 will be connected by a suitable plug with the circuit controlling the humidifier. When the humidity decreases the upper end of member 39 flexes to the left as seen in Fig. 6. This moves the upper end of segment 62 to the left swinging the gear portion thereof to the right and turning pinion 75 in a clockwise direction. This swings the hand 76 on the dial to indicate low humidity. When the humidity increases member 39 flexes to the right as seen in Fig. 6 and this correspondingly turns the hand in a counterclockwise direction as seen in said figure, turning the hand 76 to indicate increased humidity. The lower end of member 46 will flex to the left on an increase of humidity, thus breaking the engagement of members 52 and 53 and opening the control circuit for the humidifier. Upon a decrease in humidity member 46 flexes toward the right and the circuit would be correspondingly closed to call for more moisture. Strip 52 is flexible and resilient and will yield if pressed against screw 53. Upon release of such pressure it will assume its proper position. The screw 53 can be adjusted from without the casing to give the desired degree of control between the contacts 52 and 53. A very sensitive control can be had by member 46.

It is thus seen that applicant has provided a simple and efficient humidostat which will both indicate the humidity in the room and will also control a circuit extending to the humidifying apparatus. The device has been amply demonstrated in actual practice and found to be very successful and efficient. The adjustments provided can all be made from without the casing. The parts are quite few and the instrument needs little or no attention.

This application is a continuation, in part of and substitute for applicant's copending application S. N. 464,031, for "Humidostat", filed June 26, 1930, and allowed July 24, 1933.

It will, of course, be understood that various changes may be made in the form, details, arrangement and proportions of the apparatus and in the steps and sequence of steps of the method without departing from the scope of applicant's invention, which, generally stated, consists in a method and apparatus capable of carrying out the objects above set forth, such as disclosed and defined in the appended claims.

What is claimed is:—

60 1. A humidostat comprising an elongated member of wood, a waterproof covering along one side thereof, and a small metallic rod extending lengthwise of said member.

2. The structure set forth in claim 1, said rod being closely adjacent said waterproof covering.

65 3. A humidostat comprising an elongated member of wood having the grain extending transversely thereof, a waterproof covering of sheet material along one side thereof, said covering consisting of a layer of fabric material secured by waterproof adhesive, said member being fixed at one portion and having a freely movable portion.

70 4. A member for a humidostat device comprising a piece of wood treated to render the cells

thereof dead and immune to appreciable effect by temperature changes or decay and having one side sealed to protect it from moisture and arrest the fibre thereof on said side from motion due to moisture, another side being exposed so that the air has free access thereto, said piece having a fixed portion and a freely movable portion, whereby motion one way or the other of said free portion will be caused by moisture changes in the air. 10

5. A member for a humidostat device comprising a piece of wood treated chemically to fix the fibre and cells thereof but leaving the cells open for access thereto of air, one side of said piece being sealed to keep the cells firmly together but permitting bending of said piece in opposite directions without displacement of said cells from their natural position, said chemical treatment also acting to dry said piece. 15

6. A humidostat member comprising a member 20 of wood having the grain extending transversely thereof, treated chemically and by heat to render it sensitive to moisture changes in the atmosphere and substantially insensitive to temperature changes, said member being sealed against 25 moisture along one side and held from movement at one portion, whereby it will flex with moisture changes in the atmosphere.

7. The method of making a humidity responsive member which consists in forming an elongated member of wood, thoroughly drying said member, treating said member chemically to fix the fibers thereof so that the same will not deteriorate and so the same will be slightly affected by temperature changes, again thoroughly 30 drying said member and then sealing one side of said member against moisture so that said member may flex with moisture changes in the atmosphere. 35

8. The method of making a humidity responsive member which consists in forming an elongated member of hard wood with the grain extending transversely thereof, thoroughly drying said member, treating said member with permanganate of potash solution to fix the fiber 40 thereof, again thoroughly drying said member, securing one or more layers of fabric material along one side of said member by means of waterproof adhesive and the application of heat and pressure. 45

9. A humidostat comprising a member formed of dried wood chemically treated to preserve the cellular structure and sealed against moisture along one side thereof, said member being fixed at one portion and having a portion adapted to 50 flex with moisture changes in the atmosphere. 55

10. A humidostat comprising an elongated member of wood, said member being sealed at one side against moisture, and a small metallic rod embedded in said member and extending 60 lengthwise thereof.

11. The structure set forth in claim 10, said member being sealed at one side by having a layer of fabric material secured thereto by waterproof adhesive, said rod being disposed in said 65 member closely adjacent said layer.

12. A humidostat comprising a non-metallic absorbent elongated member, a waterproof covering of flexible and extensible material attached along one side thereof, means holding one end 70 of said member in fixed position, metallic means carried by the other end of said member, and a metallic rod extending lengthwise of said member.

13. A humidostat comprising a non-metallic 75

- absorbent elongated member, a waterproof covering of flexible and extensible sheet material attached along one side thereof, means holding one end of said member in fixed position, metallic means carried by the other end of said member, said metallic means being adapted to have sidewise movement with the end of said member which supports said means, and a metallic rod extending lengthwise of said member.
10. 14. A humidostat comprising an absorbent elongated member consisting of wood having the grain extending transversely thereof, a waterproof covering of flexible and extensible material attached along one side of said member, means rigidly supporting an end portion of said member in fixed position, metallic means carried by a portion of said member spaced from said supporting means, said metallic means being adapted to have sidewise movement with said member, 20 a metallic rod extending lengthwise of said member, said rod being closely adjacent said waterproof covering.
15. A humidostat having in combination, a casing, an elongated rectilinear member fixed at one end to said casing and adapted to flex with variations in humidity, said member being movable about an axis substantially perpendicular to the plane of its flexure and disposed at said fixed end, an indicating means carried by said casing, means connecting said member and indicating means for actuating the latter and means accessible from without said casing to move said member about said axis to vary the initial position of said member.
25. 16. A humidostat having in combination, a casing, a pivot post secured to said casing, an elongated member mounted adjacent one end on said pivot post and swingable thereabout but fixed against bodily transverse movement and being adapted to flex at its free end in accordance with humidity variations, a second similar elongated member rigidly secured at one end adjacent the free end of said first mentioned member and extending alongside thereof in spaced relation thereto, an electric contact carried by the free end of said second member, an adjustable contact carried by said first mentioned member adapted to be engaged and disengaged by said first mentioned contact as said second member flexes, said adjustable contact being adjustable from without said casing.
30. 17. The structure set forth in claim 16, an indicating means carried by said casing and actuated by said first mentioned member in its flexing movement.
35. 18. A humidostat having in combination, a casing, an elongated rectilinear member fixed adjacent one end in said casing and adapted to flex in accordance with humidity variations, a hand actuated by said member cooperating with said dial and means for varying the movement of said hand in response to a certain movement of said member.
40. 19. A humidostat having in combination, a casing, an elongated member fixed adjacent one end in said casing and adapted to flex in accordance with humidity variations, an indicating means carried by said casing and actuated by said member in its flexing movement, means accessible from without the casing for changing the position of said member relative to said indicating means, a second elongated member secured at one end to said first mentioned member adjacent the free end of the latter and extending alongside thereof in spaced relation thereto, a contact carried by the free end of said second member and a contact carried by said first mentioned member adjustable from without said casing adapted to be engaged and disengaged by said first mentioned contact in the flexing movement of said second member.
45. 20. A humidostat having in combination, a casing, an elongated rectilinear member fixed adjacent one end in said casing and adapted to flex in accordance with humidity variations, contacts carried by said member controlling a circuit adapted to actuate a humidifier, a dial, an indicating pointer cooperating with said dial to indicate the degree of humidity, means connecting said member and pointer, said member being movable about an axis substantially perpendicular to the plane of its flexure and disposed at its fixed end and means accessible from without said casing to move said member about said axis to vary its initial position.
50. 21. A humidostat device comprising an elongated rectilinear member of material adapted to absorb moisture, a layer of waterproof material along one side of said member, another elongated member secured to said member at one end and extending alongside thereof in spaced relation to the side opposite said layer and made of a material adapted to absorb moisture, said latter member having a layer of waterproof material secured thereto along its side remote from the side which is adjacent said first mentioned member.

EVEN J. ROHNE. 55
